UNITED STATES PATENT OFFICE.

HARRY L. BOYLE, OF OAKLAND, CALIFORNIA.

RAIL-CLIP.

1,227,526.

Specification of Letters Patent. Patented May 22, 1917.

Application filed February 8, 1917. Serial No. 147,487.

To all whom it may concern:

Be it known that I, HARRY L. BOYLE, a citizen of the United States, residing at 978 Seventy-fifth avenue, city of Oakland, in the county of Alameda, State of California, have invented certain new and useful Improvements in Rail-Clips, of which the following is a specification.

This invention relates to improvements in rail clips and has as its principal object the construction of an improved device of this character for holding a rail to the cross ties.

Another object of the present invention is to provide a device which may be cheaply constructed but which is effective in operation.

Another object is to provide a device which may be placed in position without lifting the rail from the tie and which will prevent creeping of the rail.

These and other objects in view, the invention consists of certain novel features in construction and arrangement of parts herein described and more specifically pointed out in the appended claims, it being understood that changes in form, proportion, size and minor details within the scope of the claims may be resorted to without departing from the spirit of the invention or sacrificing any of the advantages thereof.

To more fully comprehend the invention reference should be had to the drawings forming a part of the specification wherein:

Figure 1—is a view in side elevation of a rail showing the manner in which my improved clip is used to attach the same to a cross tie.

Fig. 2—is a view in cross section through one of the rails showing my improved clip in position thereon.

Fig. 3—is a view in perspective showing the clip as formed before being driven into the tie and bent around the flange of the rail.

Fig. 4—is a fragmentary view of one end of the device showing the manner in which the same is cut before the holding portions are bent.

Referring to the corresponding parts in the several views by the same numerals of reference: 1 denotes a cross tie having the rail 2 seated thereon. The rail is held to the tie by means of the usual drive spike 3, and 4 denotes in general my improved clip, which in Figs. 1 and 2 is shown attached to the rail.

This clip consists of the flat central portion 5 having similarly formed ends, each of which consists of the curved spike 6 adapted to be driven into the cross tie and shown on Fig. 1. This portion tapers from the base 8 to the point 7, and being substantially one-half the width of central portion 5. 9 denotes the lug which is adapted to be bent around the flange of the rail and which at the base 10 is substantially one-half the width of the central portion 5, and increasing in width toward the outer end 11.

It will be noted from Fig. 4 that the portions 6 and 9 are both sheared from the width of material the same as the central portion 5. They are formed by a diagonal cut 12 the two portions being then bent in a plane at right angles to that of the body 5 but in opposite directions in respect to the latter. The spike 6 is then in addition curved forwardly as plainly illustrated in Figs. 1 and 3.

In applying the device, the spikes 6 thus formed are driven into the side of the cross tie so that the upper surface of body portion 5 is positioned closely under the base flange of the rail. The lugs 9 are then bent inwardly until they contact with the upper surface of the rail flange.

It is not my intention that these clips entirely replace the usual holding spike but rather that they are auxiliary thereto. When a railway train passes over the track, the rail and tie are depressed and after the wheels have passed from a given spot the rail springs upwardly. This tends to pull the spike from the tie as the latter is held by the ballast and with increased use a spike will finally work loose and be ineffective to hold the rail. If this initial pulling out of the spike can be prevented it will firmly hold the rail and tie together. My clip aims to prevent any relative motion between the rail and tie, thus preventing the initial working loose of the spike. It will readily be seen that the construction of the clip is such that it will effectively perform this function. The clip itself is firmly bound to the rail by the bending over of the portions 9 and the ends 6 being driven into the tie substantially parallel to the bottom of the rail, the effort or the tendency of the rail to pull away from the tie exercises no tendency to withdraw the clip from the tie.

Thus when the rail is depressed it rises after the passage of the train, and the tie will be

pulled with it without any strain on the spike.

In addition if suitably placed my clip will prevent creeping of the rails. It will be understood that in bending the lugs around the base flange of the rail a firm grip is received in addition to which oxidization soon makes it impossible to move the one in respect to the other. In cases of single track lines a clip may be placed on each side of the tie or when the direction of creep is known then with the spikes pointing in that direction. In the case of multiple track systems it is well known that the rail creep is in the direction of the current of traffic. Hence if the current of traffic is in the direction of the arrow in Fig. 1 the clip is placed as there illustrated.

Now when the two are firmly bound together any creep will serve to drive the spike more firmly into the tie and the latter will resist the tendency of the rail to creep by the amount which it is embedded in the ballast.

I claim as new and wish to cover by Letters Patent:

1. A rail clip comprising, in combination with the cross tie, a body portion adapted to be positioned under the rail, lugs on each end of said body portion adapted to embrace

the base of said rail, and forwardly extending holding means adapted to be driven into the side of the tie.

2. A rail clip comprising a flat body portion, a holding lug and a tapered spike formed integrally on each end of said body portion, said spike being bent in a plane at right angles to said body portion and then curved in said plane substantially parallel to the plane of said body portion. 40

3. A rail clip, comprising a flat body portion adapted to be positioned under the rail, a tapered spike and a holding lug formed on each end of said body portion by making a diagonal cut therein, said spike portion being first bent at right angles to the surface of said body and then parallel thereto in the plane of the previously bent portion. 45

4. A rail clip comprising a flat body portion adapted to be positioned under the rail, a tapered spike and a rail embracing clip formed integrally on each end of said body by means of a diagonal cut, said spike being bent downwardly and then forwardly of said body portion to engage the cross tie and said clip being bent upwardly to engage the flanges of the rail. 50

In testimony whereof I affix my signature.

HARRY L. BOYLE.
